The ornamental design for a vertical take-off and landing aircraft, as shown and described.

DESCRIPTION

FIG. 1 is a perspective view showing the top, left side and front of a vertical take-off landing aircraft which forms a first embodiment of my new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof;

FIG. 7 is a rear elevational view thereof;

FIG. 8 is a perspective view showing the top, left side and front of a vertical take-off and landing aircraft which forms an alternate embodiment of my new design;

FIG. 9 is a top plan view thereof;

FIG. 10 is a left side elevational view thereof;

FIG. 11 is a bottom plan view thereof;

FIG. 12 is a right side elevational view thereof;

FIG. 13 is a front elevational view thereof; and,

FIG. 14 is a rear elevational view thereof.

The broken lines in the drawings illustrate portions of the vertical take-off and landing aircraft that form no part of the claimed design.
